HYDRAULIC CYLINDRICAL GRINDING
MACHINE

Herbert A. Silven, Worcester, Mass., assignor to
Norton Company, Worcester, Mass., a corpora-
tion of Massachusetts

Application November 16, 1944, Serial No. 563,683

10 Claims. (Cl. 51—95)

This invention relates to grinding machines, and more particularly to a hydraulically operated cylindrical grinding machine.

One object of the invention is to provide a simple and thoroughly practical cylindrical grinding machine. Another object of the invention is to provide a hydraulically operated cylindrical grinding machine with a main control valve mechanism which is arranged to control the various mechanisms of the machine. Another object of the invention is to provide a hydraulic cylindrical grinding machine with a main control valve which is actuated by and in timed relation with the manually operable feed mechanism so as to control the grinding wheel feed, the work table reciprocation, the disconnection of the manually operable traverse mechanism during hydraulic reciprocation of the work table, and also the stopping and starting of the work drive motor.

Another object of the invention is to provide a hydraulically operated feeding mechanism which is operated by and in timed relation with the shifting of the table reversing valve to cause a predetermined infeeding movement at table reversal. Another object of the invention is to provide an improved table reversing valve, in which an adjustable dwell control valve is provided to permit an adjustable but predetermined dwell of the table at reversal in a traverse grinding operation. Another object of the invention is to provide a hydraulically operated grinding machine with a main control valve which is actuated by manual operation of the feed mechanism to control the shifting of the feed control valve for positioning the grinding wheel either in an inoperative position or in a grinding position. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

One embodiment of the invention has been illustrated in the drawings, in which:

Fig. 1 is a front elevation of the improved hydraulically operated cylindrical grinding machine;

Fig. 2 is a diagrammatic illustration of the hydraulic control mechanism and a simplified electrical diagram of the work driving mechanism;

Fig. 3 is a fragmentary front elevation, on an enlarged scale, of the wheel feeding mechanism

as shown in Fig. 1, having the manually operable feed wheel removed;

Fig. 4 is a fragmentary cross sectional view, on an enlarged scale, through the manually operable feeding mechanism, taken approximately on the line 4—4 of Fig. 1;

Fig. 5 is a fragmentary sectional view, on an enlarged scale, taken approximately on the line 5—5 of Fig. 3, showing the hydraulically operated infeeding mechanism;

Fig. 6 is a fragmentary sectional view, partly in elevation, taken approximately on the line 6—6 of Fig. 3;

Fig. 7 is a fragmentary sectional view, taken approximately on the line 7—7 of Fig. 3, through the load and fire mechanism for actuating the main control valve;

Fig. 8 is a fragmentary sectional detail view through the latch pin for latching the hydraulically operated feed gear in an operative hand or manual feeding position;

Fig. 9 is a similar fragmentary sectional view showing the position of the eccentric latching pin when the parts are in position for an automatic infeeding operation; and

Fig. 10 is a fragmentary detail view, on an enlarged scale, of the adjusting and stop mechanism for the dwell control valve.

An improved hydraulically operated cylindrical grinding machine has been illustrated in the drawings comprising a base 10 which serves as a support for longitudinally reciprocable work supporting table 11. The table 11 is arranged to be traversed or reciprocated longitudinally on a flat way 12 and a V-way 13 formed on the upper surface of the base 10. The table 11 may be traversed longitudinally by a manually operable hand wheel 14 through a manual traverse mechanism to be hereinafter described.

A fluid pressure mechanism is provided for reciprocating the table 11 longitudinally comprising a cylinder 15 which is fixed relative to the base 10. The cylinder 15 contains a slidably mounted piston 16 which is fixedly connected to a double end piston rod 17. The opposite ends of the piston rod 17 are connected by depending brackets 18 and 19 fixedly mounted on the under side of the table 11 at its opposite ends.

A table reversing or control valve 20 is provided for controlling the admission to and exhaust of fluid from the cylinder 15. When fluid under pressure is passed through a pipe 21 and a pipe or passage 22 into a cylinder chamber 23, it will cause the piston 16 and the table 11 to move

toward the right (Fig. 1). During the movement of the piston 16 toward the right, fluid within a cylinder chamber 24 will exhaust through a pipe or passage 25 and through a pipe 26 to the control valve 20.

The work table 11 serves as a support for a rotatable work piece 21. The work piece 21 is supported on a headstock center 28 and a footstock center 29 which are in turn supported by a headstock 30 and a footstock 31, respectively. The headstock 30 is preferably a motor driven headstock comprising an electric motor 32 which is provided with a driving pulley 33 (Fig. 2) which is connected by multiple V-belts 34 with a pulley 35 to drive the work piece 21 during a grinding operation.

A transversely movable wheel slide 38 is arranged to move transversely relative to the base 10 on a V-way 39 and a flat way 40 (Fig. 1). The wheel slide 38 is provided with a rotatable wheel spindle 41 which supports a grinding wheel 42 at its left-hand end. The spindle 41 and grinding wheel 42 are preferably positively driven by any suitable means such as, for example, an electric motor 43 which is mounted on the upper surface of the wheel slide 38. The motor 43 is provided with an armature shaft 44 which supports a multiple V-groove pulley 45. The pulley 45 is connected by multiple V-belts 46 with a multi-V-groove pulley 47 which is mounted on the right-hand end of the wheel spindle 41.

A nut and screw feeding mechanism is provided for feeding the wheel slide 38 transversely relative to the base 10. This mechanism may comprise a rotatable feed screw 50 which meshes with a depending half nut 51 fastened to the under side of the wheel slide 38. A reduced end portion 52 of the feed screw 50 is slidably keyed within a rotatable sleeve 53. The sleeve 53 is journaled in anti-friction bearings 54 and 55 which are in turn fixed relative to the base 10. The right-hand end of the feed screw 50 is journaled in suitable bearings (not shown) in a slidably mounted sleeve 56 which is slidably keyed within a portion of the base 10.

In order to move the wheel slide 38 rapidly to and from a grinding position, a hydraulically operated mechanism is provided comprising a hydraulic cylinder 57 which contains a slidably mounted piston 58. The piston 58 is connected to a double end piston rod 59, the left-hand end of which is fastened to the slidably mounted sleeve 56. As illustrated in Fig. 2, the piston rod 59 is arranged in axial alignment with the axis of the feed screw 50.

A control valve 60 is provided to control the admission to and exhaust of fluid from the cylinder 57. When fluid under pressure is admitted through a pipe 61 into a cylinder chamber 62, it will cause the piston 58, the feed screw 50, and the wheel slide 38 to move to an operative position relative to the work piece 21 to be ground. During this movement, fluid within a cylinder chamber 63 exhausts through a pipe 64. Similarly, when fluid under pressure is admitted to the cylinder chamber 63, the piston 58, wheel slide 38 and grinding wheel 42 will move to a rearward or inoperative position.

A manually operable feed wheel 10 is provided for manually rotating the feed screw 50 to impart a transverse feeding movement to the wheel slide 38 (Fig. 4). The feed wheel 10 is rotatably supported on a reduced cylindrical end portion 11 of a rotatable shaft 12. The shaft 12 is rotatably

is fixed relative to the base 10 and its other end is rotatably supported in a sleeve bearing 14 which is also fixed relative to the base 10.

The feed wheel 10 is provided with an old and well known micrometer adjusting mechanism 15 which is substantially the same as that shown in the expired U. S. Patent No. 762,838 to C. H. Norton dated June 14, 1904, to which reference may be had for details of disclosure not contained herein. The micrometer feed adjusting mechanism 15 is provided with a pinion 16 which meshes with a gear 17. The gear 17 is pinned to the shaft 12. A pinion 18 is formed adjacent to the right-hand end of the shaft 12. The pinion 18 meshes with a gear 19 which is rotatably supported on a stud 20. The gear 19 in turn meshes with a gear 21 which is formed integral with the sleeve 22. It will be readily apparent from the foregoing disclosure that a rotary motion of the manually operable feed wheel 10 will be imparted through the micrometer adjusting mechanism 15 to rotate the gear 17 which in turn rotates the shaft 12 and through the gear mechanism above described serves to transmit a rotary motion to the feed screw 50 to transmit a transverse feeding movement through the half nut 51 to the wheel slide 38 and the grinding wheel 42.

A power operated feeding mechanism is provided for rotating the feed screw 50 intermittently at the ends of the table stroke for a traverse grinding operation. This mechanism is preferably hydraulically operated comprising a rotary vane type fluid motor 85 having a rotatable rotor shaft 86. A rotor 87 is formed integral with the shaft 86 and serves as a support for a single vane 88 (Fig. 2). A fixed plate 89 within the motor 85 serves to limit the rotary motion of the vane 88. When fluid under pressure is admitted through a passage 90 into a cylinder chamber 91, the rotor 87 and vane 88 will be moved in a counterclockwise direction (Fig. 2) to cause an infeeding movement of the grinding wheel 42. During this movement, fluid within a motor chamber 92 will exhaust through a passage 93.

A control valve 95 is provided for controlling the admission to and exhaust of fluid under pressure to the motor 85. The valve 95 comprises a valve stem 96 having a plurality of valve pistons formed integrally therewith so as to form valve chambers 97, 98, 99, 100 and 101. When fluid under pressure is passed through a pipe 102 in a manner to be hereinafter described, it will enter the valve chamber 99 and pass through passage 90 into motor chamber 91 to start a counterclockwise rotation of the vane 88 to produce an infeeding movement of the grinding wheel. The valve 95 is preferably hydraulically actuated in timed relation with the other mechanisms of the machine. A pipe 103 is connected with the valve chamber 101 and serves to convey fluid under pressure to move the valve stem 96 to its extreme left-hand end position (Fig. 2). Similarly, a pipe 104 is connected at the other end of the valve 95 to admit fluid to or exhaust fluid from the valve chamber 97 formed at the left-hand end of the valve 95. When fluid under pressure is passed through the pipe 104 into the chamber 97, the valve stem 96 will be moved toward the right (Fig. 2). During the shifting movement of the valve stem 97 toward the right, as the valve chamber 99 is opened to the pressure pipe 102, fluid under pressure will be passed through the passage 90 into the motor chamber 91 to start a counterclockwise movement of the vane 88 to

wheel. This movement continues until the valve chamber 99 moves out of communication with the passage 98 and is positioned to pass fluid under pressure from the pipe 102 through the valve chamber 99, the passage 98, into the motor chamber 92 to move the vane 88 in a clockwise direction to return the grinding wheel to its initial position. Similarly, at the other end of the table stroke, when fluid under pressure is passed through the pipe 102 into the valve chamber 101, the valve stem 96 will be shifted toward the left. During the movement of the valve stem toward the left, fluid under pressure will first be admitted from the pipe 102 through the valve chamber 99 into the passage 98 and the motor chamber 91 to initiate an infeeding movement of the grinding wheel, after which fluid will be admitted from the pipe 102 through the valve chamber 100 (Fig. 2), through the passage 95, into the motor chamber 92, to move the vane 88 in a clockwise direction to return it to its initial position. It will thus be seen that during each shifting movement of the valve stem either toward the right or toward the left, the vane 88 will first be moved in a counterclockwise direction to feed the grinding wheel into the work, after which the vane 88 is moved in a clockwise direction to return the grinding wheel to its initial position.

The rotor shaft 86 of the motor 85 is provided at its outer end with a gear 110 which is keyed thereto. The gear 110 meshes with a gear 111 which is mounted on a rotatable sleeve 112. The sleeve 112 is connected by a one-way ball clutch 113 with a rotatable sleeve 114 which supports a gear 115. The sleeve 112 is rotatably supported on anti-friction bearings carried by a stud 116 which is fixedly supported within a casing 117. The casing 117 is preferably fixedly mounted to a flange 118 which is formed integral with a rotatable sleeve 119. The sleeve 119 is journaled within an aperture 120 which is formed integral with the motor 85. The casing 117 is arranged so that the gear 115 may be moved in a clockwise direction into either position 115a or 115b. In the position 115a, a stop abutment 121 which is fixed relative to the casing 117 (Figs. 1 and 3) may be swung into position 121a in the path of a stop abutment 122 carried by the manually operable hand wheel 70. The abutment 121a serves as a positive stop to limit the rotary infeeding movement of the hand wheel 70.

The casing 117 which supports the feed gearing may be moved to an operative position, in which position a slidably mounted latch stud 123 having a reduced eccentric portion or pin 124 may slide into engagement with an aperture 125 which is fixed relative to the base of the machine. The engagement of the pin 124 with the hole 125 serves to lock the casing 117 so that the gear 115 will be located either in position 115a or 115b. The pin 124, which is formed integral with the latch stud 123, is preferably eccentrically mounted relative thereto so that in the position illustrated in Figs. 6 and 8, it will position the feeding gear 115 in position 115a for a hand feeding operation. If it is desired to provide a power infeeding movement of the grinding wheel, the latch stud 123 may be rotated by means of a knob 126 to shift the position of the eccentric stud 124 so that the casing 117 is rocked relative to the aperture 125 so that the driving gear 115 will move into position 115b in mesh with the gear 71. It will be readily apparent from the foregoing disclosure that a rotary motion of the vane 88

of the motor 85 will be transmitted through the gear mechanism above described to rotate the gear 71, which movement in turn will be transmitted through the shaft 72 to rotate the feed screw 50 and thus impart an infeeding movement to the grinding wheel 42.

The one-way ball clutch 113 which is located between the sleeves 112 and 114 serves to transmit the rotary motion of the vane type motor to rotate the gear 71 when the vane is moved in a counterclockwise direction to cause an infeeding movement of the grinding wheel. When the fluid under pressure is reversed to rotate the vane 88 in a clockwise direction, the ball clutch 113 will slip so that the rotary motion of the gear 111 will not be transmitted to cause a rotary motion of the gear 115 so that the vane type motor 85 may be returned to its initial position (Fig. 2) without turning the feed screw.

In order to facilitate setting up the machine, it is desirable to provide a suitable adjusting mechanism whereby the vane 88 of the fluid motor 85 may be adjusted relative to the casing 117. This is preferably accomplished by providing an adjusting knob 130 which supports a graduated dial 131. An index or zero marker 132 is provided on the casing 117. A clamp mechanism is provided comprising a bracket 133 having a clamping screw 134 which is screw threaded into housing 117. When it is desired to adjust the position of the vane relative to the casing 117, the screw 134 may be loosened and the knob 130 rotated to the desired extent, after which the screw 134 again may be clamped to lock the parts in adjusted position.

A suitable stop mechanism is provided for limiting the swinging movement of the housing 117 in a counterclockwise direction. This mechanism may comprise a stop pin 135 which is fixed relative to the base 10 of the machine. A projecting lug 136 formed on the casing 117 is positioned to engage the stop pin 135 and thus restrict the counterclockwise swinging movement of the housing 117.

In order to facilitate movement of the feed gearing into an operative position, a manually operable lever 137 is pivotally mounted on a stud 138 (Figs. 3, 5 and 6) which is carried by the housing 117. The lower end of the lever 137 is provided with an aperture 139 which surrounds the outwardly projecting portion of the stud 123. The lever 137 may be swung in a clockwise direction (Figs. 1 and 3) to throw the gear 115 into an operative position. When it is desired to disconnect the power feed gear from an operative position, the lever 137 may be swung in a counterclockwise direction (Fig. 6) to withdraw the latch pin 123, that is, to move it toward the right (Fig. 6) to withdraw the eccentric end portion 124 out of engagement with the locating hole 125 and the released tension of a spring 140 will shift the housing 117 to an inoperative position with the gear 115 in the full line position as indicated in Fig. 3. The spring 140 is connected between a stud 141 which is fixed relative to the base 10 and a stud 142 which is fixedly mounted on the casing 117.

The wheel feed control valve 60 is preferably a piston type valve comprising a valve stem 145 having formed integrally therewith valve pistons 146, 147 and 148. An actuating knob 149 is fixedly mounted on the outer end of the valve stem 145. The valve stem 145 is arranged so that if desired it may be locked in either a right-hand or a left-hand end position (Fig. 2) by means of

a pin 150. A pair of transverse grooves 151 and 152 are provided in the valve stem 145. These slots 151 and 152 are connected by a longitudinally extending slot 153. When the slot 153 is aligned with the pin 150, the valve stem 145 may be moved longitudinally, as desired. If it is desired to latch the valve in either a right-hand or a left-hand end position (Fig. 2), the valve stem 145 is moved into the desired position and the knob 149 rotated so that the pin 150 engages either the groove 151 or the groove 152 to lock the valve stem 145 so that the wheel slide 38 will be maintained either in a forward operative position or in a rearward inoperative position.

In the position of the valve 60 as shown in Fig. 2, fluid under pressure passing through a pipe 154 enters a valve chamber 155 located between the valve pistons 146 and 147 and passes out through the pipe 64 into the cylinder chamber 63 to move the piston 58 and wheel slide 38 into a rearward or inoperative position. During this movement of the piston 58, fluid within the cylinder chamber 62 exhausts through the pipe 61 into a valve chamber 156 located between the valve pistons 147 and 148 and passes out through a pipe 157 into a reservoir 158.

It is desirable that the wheel feeding mechanism be arranged so as to initiate a grinding cycle, that is, so that when a work piece 27 has been mounted in position on the machine, the operator is merely required to turn the feed wheel 70 to start a forward feeding movement of the grinding wheel 42, to start a reciprocatory movement of the work supporting table 11 and to start the headstock driving motor 32 and to disconnect or render the manually operable traverse wheel 14 inoperative during the grinding operation. This is preferably accomplished by providing a main control valve 160. The valve 160 is preferably a piston type valve comprising a valve stem 161 having formed integrally therewith valve pistons 162, 163, 164 and 165. A spool-shaped member 166 is mounted on the outer end of the valve stem 161. The member 166 is provided with a groove 167 which is connected by a pair of opposed studs 168 (Fig. 4) with a rock arm 169. The rock arm 169 is fixedly mounted on a rock shaft 170.

A load and fire mechanism is supported on the forward end of the rock shaft 170 and comprises a flanged member 171 which is pinned to the rock shaft 170. The flanged member 171 serves as a support for a pair of pivotally mounted members 172 and 173 each of which is arranged to engage a stud 174 which is fixedly mounted on the flanged member 171. The members 172 and 173 are normally maintained in engagement with the stud 174 by means of a tension spring 175 which is connected by the studs 176 and 177 which are fixedly mounted on the members 172 and 173, respectively. The upper ends of the members 172 and 173 are provided with cam faces 178 and 179 which are staggered or offset relative to each other and are arranged to be engaged by a pair of offset cam members 180 and 181, respectively, which are formed on a bracket 182. The bracket 182 is in turn supported on an adjustable collar 183 which is supported on an inner hub portion of the hand wheel 70. The collar 183 is arranged to be locked in adjusted position by means of a clamping screw 184 which passes through the hand wheel 70 and engages a nut 185 which is slidably mounted in a T-shaped arcuate groove 186 extending around the collar 183 (Figs. 3 and 4).

It will be readily apparent from the foregoing disclosure that when the hand wheel 70 is rotated, either the cam 180 or the cam 181 will engage the cam faces 178 or 179 respectively to rock either the member 172 or the member 173 and through the pin 174 to rock the shaft 170 and thereby shift the valve stem 161 to shift the position of the main control valve 160 so as to start or stop a grinding operation, as desired. A spring-pressed detent 187, which is fixedly mounted relative to the base 10, is arranged in the path of an arrow-point stud 188 which is fixedly mounted on the flanged member 171 by means of which the valve 161 may be rapidly shifted into a reverse position when actuated by either the member 172 or the member 173.

Hand traverse

A manually operable traverse mechanism is provided for manually adjusting the table 11 longitudinally relative to the base 10. This mechanism is actuated by the manually operable traverse wheel 14 which is rotatably mounted on a stud 190. A gear 191 is fixed to rotate with the hand wheel 14. The gear 191 meshes with a gear 192. The gear 192 is keyed to a shaft 193. The shaft 193 also supports a gear 194 which meshes with a gear 195. The gear 195 is rotatably supported on a stud 196 and meshes with a rack bar 197 depending from the under side of the work table 11.

It is desirable to render the hand wheel 14 inoperative so that it will remain stationary during the hydraulic traverse or reciprocation of the table 11. The gear 194 is preferably rotatably supported on the shaft 193 and is provided on its right-hand side face (Fig. 2) with clutch teeth 198 which are arranged to be engaged by clutch teeth formed on a slidably mounted clutch member 199 which is slidably keyed to the shaft 193. In order to disconnect the clutch parts 198-199, a fluid pressure cylinder 200 is provided which contains a slidably mounted piston 201. The piston 201 is fixedly mounted on the right-hand end of the clutch member 199. In the position of the mechanism as illustrated in Fig. 2, the clutch parts 198-199 are maintained in engagement by means of a plurality of compression springs 202 (only one of which has been illustrated in Fig. 2). When it is desired to disconnect the hand wheel during hydraulic traverse of the table 11, fluid under pressure is passed through a pipe 203 to the cylinder chamber 204 to move the piston 201 toward the right (Fig. 2) so as to disconnect the clutch parts 198-199, thereby rendering the manually operable traverse wheel 14 inoperative.

Headstock motor control

It is desirable to provide a suitable control mechanism for automatically starting and stopping the headstock motor 32 in timed relation with the other mechanisms of the machine. Power is supplied to the motor 32 from power lines 205. A push button switch 206 is provided for closing the motor circuit. It is preferable to provide a motor 32 which is of a variable speed type so that the speed of rotation of the work piece 27 may be readily adjusted. As shown diagrammatically in Fig. 2, an adjustable rheostat 207 is provided for regulating the speed of the motor 32. In actual construction, however, an electronic control mechanism is preferably provided, such as that for example manufactured by General Electric Company and known as the "Thymotrol." A normally open limit switch 207 is provided in the motor

circuit to facilitate automatically starting the motor in timed relationship with the other mechanisms of the machine. A hydraulically operated mechanism is provided for actuating the limit switch 208 comprising a hydraulic cylinder 209 which contains a slidably mounted piston 210. A piston rod 211 is connected at one end with the piston 210 and at the other end engages a roller 212 mounted on an actuating arm 213 of the limit switch 208. A compression spring 214 normally maintains the piston 210 in an uppermost position (Fig. 2) so that the switch 208 is normally open.

When fluid under pressure is passed through a pipe 215 into a cylinder chamber above the piston 210, the piston 210 moves downwardly against the compression of the spring 214 to close the normally open limit switch 208 and thus automatically to start the rotation of the headstock motor 32. Similarly when fluid is permitted to exhaust through the pipe 215, the released compression of the spring 214 will return the piston 210 to its uppermost position to open the limit switch 208 and thereby stop the motor 32.

The main control valve 160 is operatively connected automatically to shift the feed control valve 60 so as to cause either a forward or a rearward movement of the grinding wheel 42. A valve chamber 216 located between the valve pistons 163 and 164 is connected by a pipe 217 with a valve chamber 218 formed at the right-hand end of the valve 60. Similarly, a valve chamber 219 formed between the valve pistons 164 and 165 of the valve 160 is connected by a pipe 220 with a valve chamber 221 formed at the left-hand end of the valve 60 (Fig. 2). The pipe 215 connects with the pipe 217 so that when fluid under pressure is passed through the pipe 217 to shift the valve 60 toward the left to initiate a forward feeding movement of the grinding wheel, fluid will also be passed from the pipe 217 through the pipe 215 to close the limit switch 208 and thereby start the rotation of the work piece 21.

Table reversing valve

The table reversing valve 20 is preferably a piston type reversing valve. A shuttle type reversing valve member 225 is provided having valve pistons 226, 227 and 228 formed integrally therewith. The reversing valve 225 is preferably slidably mounted on a valve stem 229. A pair of independent pilot valves 230 and 231 are fixedly mounted on the right-hand end of the valve stem 229 (Fig. 2). The spool-shaped member 232 is provided with a groove 233 which is engaged by a stud 234 which is in turn fixedly mounted on a rock arm 235. The rock arm 235 is fixedly mounted on a rock shaft 236. A table actuated reversing lever 237 is fixedly mounted on the outer end of the rock shaft 236 and is provided at its upper end with a pin or stud 238 which is arranged to be actuated by a pair of adjustable table dogs 239 and 240. The table dogs 239 and 240 are adjustably supported by means of a longitudinally extending T-shaped slot 241 formed in the front edge of the work table 11.

A motor driven fluid pressure pump 245 is provided for supplying fluid under pressure to the hydraulic system. The pump 245 draws fluid through a pipe 246 from the reservoir 158 and passes fluid under pressure through a pipe 247 to the various mechanisms of the machine. A relief valve 248 is connected in the pipe line 247 to facilitate maintaining the desired operating pressure within the hydraulic system. If pres-

sure builds up beyond the predetermined pressure required, the relief valve 248 opens and bypasses excess fluid under pressure directly to the reservoir 158.

5 The pipe 247 is connected to supply fluid under pressure to the table reversing valve 20. In the position of the valve 20 illustrated in Fig. 2, fluid under pressure from the pipe 247 enters a valve chamber 249 located between the valve pistons 226 and 227 and passes out through the pipe 21 into the cylinder chamber 23 to cause the piston 16 and table 11 to move toward the right (Figs. 1 and 2). During this movement of the table, fluid within the cylinder chamber 23 exhausts through the pipe 26 and through a valve chamber 250 located between the valve pistons 227 and 228 and passes out through an exhaust pipe 261.

A stop and start valve 252 is provided for controlling the exhaust of fluid from the reversing valve 20. This valve 252 is a piston type valve comprising a valve stem 253 having formed integrally therewith valve pistons 254, 255, 256 and 257. In the position of the valve illustrated in Fig. 2, a by-pass is provided to facilitate a manual traversing of the work table 11. A pipe 258 connects the valve chamber 249 in the valve 20 with a chamber 259 formed in the stop and start valve 252. A similar pipe 260 connects the valve chamber 250 of the valve 20 with the chamber 259 of the stop and start valve 252. It will be readily apparent from the foregoing disclosure that when the table 11 is traversed manually by rotation of the traverse wheel 14, fluid may readily by-pass from the cylinder chamber 23 through the reversing valve 20, through the by-pass chamber 259 in the stop and start valve 252, and into the cylinder chamber 24, thus allowing a free manual traverse without the necessity of overcoming the resistance of oil or fluid within the hydraulic system.

40 The stop and start valve 252 is provided with a V-port 261 which is arranged so that when the valve stem 253 is moved toward the left (Fig. 2) to start hydraulic operation of the machine, fluid exhausting through the pipe 251 from the reversing valve 20 will pass through the V-port 261 and out through a pipe 262. The pipe 262 is connected to exhaust fluid into a valve chamber 263 located between the valve pistons 162 and 163 of the main control valve 160. In the position of the 45 main control valve 160, the exhaust of fluid is confined within the chamber 263 and, the V-port 261 being closed, no traversing movement of the table may be obtained under fluid pressure. When it is desired to start a hydraulic traversing movement 50 of the table, the start and stop valve 252 is moved toward the left by a knob 264 to open the V-port 261 which will control the rate of fluid exhausting from the table cylinder 15 and reversing valve 20. Opening the V-port 261 will not start hydraulic movement of the table since this movement does not become operative until the main control valve 160 is shifted by manual rotation of 55 the feed wheel 70.

Assuming the stop and start valve 252 has been 60 shifted to start the table traverse, and the feed wheel 70 has been rotated to shift the main control valve 160 to an operative position, fluid under pressure passing through the pipe 247 will cause the piston 16 and the table 11 to move toward the right (Figs. 1 and 2). This movement will continue until the table dog 239 engages the pin 238 to rock the reversing lever 237 in a clockwise direction. This table movement serves positively to shift the valve piston 227 of the reversing valve 20 so that it closes an exhaust port 255. During

this movement the valve member 230 engages the end of the shuttle reversing valve member 226 and moves both valve parts so that the piston 227 closes the port 265. When the valve parts reach this position, fluid under pressure passes through a passage 266 into a chamber 267 in the valve 230. Fluid under pressure entering the valve chamber 267 may pass outwardly through an exhaust pipe 268 and also may pass through a passage 269 into a valve chamber 270 formed at the left-hand end 10 of the shuttle reversing valve 225. Fluid under pressure entering the chamber 270 serves to move the shuttle type reversing valve 225 rapidly toward the right (Fig. 2) into its reverse position.

Similarly, the valve member 231 at the other 15 end of the reversing valve 20 is provided with a valve chamber 280. A passage 281 connects the valve chamber 280 with the fluid pressure pipe 247. A pipe 282 connects the valve 231 with the dwell control valve 275. A pipe 283 connects the valve chamber 280 of the valve 231 with a valve chamber 284 at the right-hand end of the shuttle valve 225.

The dwell control valve 275 is provided for controlling the rate of exhaust of fluid through pipes 268 and 282. Fluid from pipes 268 and 282 enters a chamber 276 in the dwell control valve 275 and passes through a V-port 277 and a pipe 278 which returns exhausting fluid into the reservoir 158. In the position of the valve 275 (Fig. 2), fluid is restricted by the V-port 277. This port may be regulated by means of a rotary adjustment of the valve 275 by means of a knob 279. The speed of shifting of the shuttle valve 225 in either direction will be governed by the amount of fluid exhausting through the pipes 268 and 282 and the V-port 277 so that by a slight rotary adjustment of the knob 279, the extent of dwell of the work table 11 at reversal may be readily adjusted and controlled. During a wheel truing operation or for certain grinding operations, it may be desirable 40 to provide a quick reversal without any dwell. This may be accomplished by rotating the knob 279 so that the V-port 277 is entirely open.

When the work table 11 approaches the right-hand end of its stroke, the table dog 239 engages the pin 238 to rock the reversing lever 37 in a counterclockwise direction (Fig. 1). This movement serves positively to shift the shuttle valve 225 so that the valve piston 227 covers the exhaust port 265. When the shuttle valve reaches this position, the valve 230 has moved a sufficient distance toward the right so that fluid under pressure from the pipe 247 entering the passage 266 may pass into the valve chamber 267. The port at the end of the pipe 268 has now been closed so that pressure entering the valve chamber 267 passes through the passage 269 into the valve chamber 270 to move the shuttle valve 225 toward the right into its reverse position. The speed of movement of the shifting of the shuttle valve is controlled so as to give the desired amount of dwell at the end of the table stroke. As the shuttle valve moves toward the right, fluid within the valve chamber 284 is forced out through the passage 283 into the valve chamber 280 and out through the pipe 282 to the dwell control valve 275. By regulating the V-port of the dwell control valve 275, the speed of movement of the shuttle valve 225 may be readily controlled to give the desired amount of dwell at the right-hand end of the table stroke.

Similarly, at the other end of the table stroke, when the valve stem 229 is positively moved toward the left under the influence of the table dog 240, the shuttle valve 225 will be positively 75

moved so that the valve piston 227 closes the exhaust port 265, at which time fluid under pressure from the pipe 247 will pass through the passage 281 into the valve chamber 280 and through the passage 283 into the valve chamber 284 to shift the shuttle valve 225 toward its left-hand end position. The speed of movement of the throttle valve in the left-hand direction will be controlled by fluid exhausting from the valve chamber 270 through the passage 269 and the pipe 268 which passes fluid through the V-port 277 of the dwell control valve 275.

In order that a wheel feeding movement may be obtained at reversal in a traverse grinding operation in timed relation with the table movement, it is desirable to provide a control valve to control the shifting movement of the feed control valve 95. A control valve 290 is provided. This valve is a piston type valve comprising a valve stem 291. The arm 235 which actuates the reversing valve 20 is provided with an upwardly extending arm 292 which is provided with a stud 293. The stud 293 engages a slot 294 formed in the valve stem 291. Fluid under pressure from the pipe 247 passes through a pipe 295 into a valve chamber 296 in the valve 290 and in the position of the valve (Fig. 2) passes outwardly through the pipe 103 into the valve chamber 101 in the valve 95 to shift the valve 95 toward the left so that fluid under pressure within the pipe 295 may pass through the pipe into the valve chamber 100 and into the motor chamber 92 to cause the vane 88 to move in a clockwise direction into the position illustrated in Fig. 2. When the reversing lever 237 is moved in a clockwise direction (Fig. 1) so as to cause a similar movement of the arm 235 and its extension 292, also in a clockwise direction to reverse the reversing valve 20, a corresponding reversing motion is also imparted to the valve stem 291 of the valve 290 so that fluid under pressure from the pipe 295 entering the valve chamber 296 will pass outwardly through the pipe 104 which conveys fluid under pressure to the valve chamber 97 in the valve 95 to cause the valve stem 96 to move toward the right (Fig. 2). During the movement of the valve stem 96 toward the right the valve pistons are shifted so that fluid under pressure passing through the pipe 102 first enters a valve chamber 99 in the valve 95 and passes through the passage 90 into the motor chamber 91 to cause the vane 88 to move in a counterclockwise direction so as to impart a feeding movement to the grinding wheel at both ends of the table stroke. As the valve 95 approaches its right-hand end position, fluid under pressure entering the valve chamber 99 will pass through the passage 93 into the motor chamber 92 to return the vane 88 in a clockwise direction into its initial position (Fig. 2). During the return clockwise movement of the vane 88, the ball clutch 113 slips or idles so that rotation of the gears 110 and 111 during the return stroke will not be transmitted to the gear 115.

In order to facilitate rapid adjustment of the dwell control valve 275 so that no dwell may be obtained for such operations as wheel truing and for quick return to the predetermined table dwell for traverse grinding, an adjustable detent 300 is adjustably fastened to the front of the machine base. The downwardly extending portion of the detent 300 is arranged in the path of a stud 301 which projects inwardly from the knob 279 (Fig. 10). A stop pin 302 is fixedly mounted relative to the base of the machine and serves to limit the rotation of the knob 279 when turned in a

counterclockwise direction (Fig. 10). When the knob 279 is turned in a counterclockwise direction so that a pin 301 engages a fixed pin 302, the valve 275 is positioned so that the V-port 277 is opened to permit a maximum exhaust of fluid from either the valve chamber 270 or the valve chamber 284 so as to provide a rapid shifting of the reverse valve 225 with a minimum amount of dwell or no dwell at reversal. Similarly, when the knob 279 is rotated in a clockwise direction so that the stud 301 engages the detent 300, the dwell control valve 275 will be positioned so that the V-port 277 is closed a predetermined amount to allow the desired dwell at table reversal.

The operation of this improved cylindrical grinding machine will be readily apparent from the foregoing disclosure. A work piece 27 is mounted in position on the headstock center 28 and footstock center 29. The motor driven pump 245 is started and also the motor 43 for rotating the grinding wheel 42. The start and stop valve knob 264 is then moved toward the left (Fig. 2) to open the V-port 261. The lever 137 is shifted in a clockwise direction to shift the gear 115 either into position 115a or 115b, as above described. In case it is desired to provide a power infeed at the ends of the table stroke on a traverse grinding operation, the gear 115 is moved to position 115b. The hand feed wheel 10 is then rotated manually in a counterclockwise direction. This movement serves through the cam 181 (Fig. 3), which rotates with the hand wheel 70, to engage the cam 178 and thereby rock the shaft 170 so as to shift the main control valve 160 toward the right (Fig. 2) to start the grinding cycle. When the valve 160 moves to its extreme right-hand end position, fluid under pressure is passed through the pipe 217 into the valve chamber 218 of the valve 60 to shift the feed valve toward the left (Fig. 2), which movement serves to admit fluid under pressure through the pipe 61 into the cylinder chamber 62 of the feed cylinder 57 to cause the piston 58, the feed screw 59, the wheel slide 38 and the grinding wheel 42 to move forward toward an operating position. This movement continues until the piston 58 engages the end face of the cylinder 57. At the same time as the valve 160 is moved into its right-hand end position, fluid under pressure is admitted through the pipe 215 into the cylinder chamber to cause the piston 210 to move downwardly to close the limit switch 208 and thus to start the work drive motor 32. The opening of the stop and start valve 252 serves to allow fluid under pressure to pass through the pipe 203 into the cylinder chamber 204 to shift the clutch member 199 toward the right and thereby to render the manually operable table traverse wheel 14 inoperative.

In the position of the parts as shown in Figs. 1 and 2, when the grinding cycle is started, the table 11 starts moving toward the right and continues movement in this direction until the dog 239 engages the pin 238 to rock the reversing lever 237 in a clockwise direction. This movement serves in the manner above described to shift the reversing valve 20 into its reverse position to change the direction of flow of fluid under pressure to the table cylinder 15. At the same time the reversing valve 20 is shifted, the rock arm 235, through its extension 292 serves to shift the valve stem 291 of the valve 290 toward the right (Fig. 2), which movement serves to admit fluid under pressure through the pipe 104 into the valve chamber 97 to shift the valve stem 96

of the valve 95 toward the right so that fluid under pressure passing through the pipe 102 will pass through the passage 90 into the motor chamber 91 to move the motor vane 88 in a counterclockwise direction. This movement is transmitted through the gear mechanism in the manner above described to transmit a counterclockwise movement to the gear 71 so as to impart an infeeding movement of the grinding wheel through the feed screw 50 at the end of the table stroke. During the shifting movement of the valve stem 96 toward the right, fluid passing through the pipe 102 first enters through the passage 93 to initiate an infeeding movement of the grinding wheel. When the valve stem 96 approaches its extreme right-hand end position, fluid under pressure passing through the pipe 102 and the valve chamber 99 will enter through the passage 93 into the motor chamber 92 to initiate a return clockwise movement of the vane 88, thus returning the vane to its initial position. During the return stroke of the vane 88, the ball clutch 113 allows rotation of the gears 110 and 111 in the reverse direction without transmitting this motion to the gear 115 so that at each reversal of the table, the vane motor 85 rotates to cause a predetermined infeeding movement of the grinding wheel 42 and then returns idly to its initial position, such as shown in Fig. 2 of the drawings.

This cycle of operation is continued and the table 11 allowed to reciprocate until the work piece has been ground to the desired and predetermined extent, that is, until the stop abutment 122 on the feed wheel 70 engages the stop abutment 121b which positively limits the infeeding movement of the grinding wheel as imparted by the feed screw 50.

When the grinding operation has been completed, the operator shifts the lever 137 toward the front of the machine, that is, in a counterclockwise direction (Fig. 6) to draw the latch stud 124 from the hole 125 which releases the tension of the spring 140 so that the released tension of the spring will return the feed gear 115 into full line position (Fig. 3). The hand feed wheel 70 may then be rotated in a counterclockwise direction until the cam face 180 engages the cam face 178 to rock the member 172 and thereby to rock the shaft 170 and the arm 169 to shift the main control valve piston 161 into its left-hand end position, such as shown in Fig. 2. The shifting of the valve 160 into this position serves to admit fluid under pressure through the pipe 220 to shift the feed control valve 60 under the influence of fluid pressure into its right-hand end position (Fig. 2) so that fluid is admitted through the pipe 64 into the cylinder chamber 63 to cause the piston 58 and the grinding wheel slide 38 to move rearwardly to an inoperative position. At the same time, fluid is permitted to exhaust from the cylinder chamber through the pipe 215 so that the released compression of the spring 214 serves to allow the limit switch 208 to open, thus stopping the rotation of the work drive motor.

When it is desired to traverse the table 11 manually, the stop and start valve 252 must be shifted toward the right into the position illustrated in Fig. 2 so that fluid under pressure may exhaust from the cylinder chamber 204 to allow the released compression of the springs 202 to move the clutch member 199 toward the left into the position illustrated in Fig. 2 so that rotation of the manually operable traverse wheel 14 will impart a longitudinal motion to the rack bar 197.

and the table 11 through the traverse gear mechanism above described.

It will thus be seen that there has been provided by this invention apparatus in which the various objects hereinabove set forth together with many thoroughly practical advantages are successfully achieved. As various possible embodiments might be made of the mechanical features of the above invention and as the art herein described might be varied in various parts, all without departing from the scope of the invention, it is to be understood that all matter hereinbefore set forth or shown in the accompanying drawings is to be interpreted as illustrative and not in a limiting sense.

I claim:

1. In a grinding machine having a base, a reciprocable table thereon, a piston and cylinder to reciprocate said table and a reversing valve therefor comprising a control valve having a table actuated valve stem, a reversing valve slidably mounted on said valve stem, a pilot valve fixedly mounted on each end of said valve stem to control the shifting movement of the reversing valve, valve chambers located between the pilot valves and the ends of said reversing valve, and a dwell control valve connected with each of said pilot valves which is arranged to control the shifting of the reversing valve so as to produce the desired dwell during table reversal.

2. In a grinding machine having a base, a reciprocable table thereon, a piston and cylinder to reciprocate said table and a reversing mechanism therefor comprising a control valve having a table actuated valve stem, a pilot valve fixedly mounted adjacent to each end of said stem, a reversing valve between said pilot valves which is slidably mounted on said valve stem, valve chambers between the pilot valves and the ends of said reversing valve, and a dwell control valve connected with each of said pilot valves, said parts being arranged so that the table movement positively shifts the valve stem, pilot valves and reversing valve until the reversing valve cuts off the exhaust of fluid from said cylinder, in which position one of said pilot valves admits fluid under pressure to the adjacent valve chamber to shift the reversing valve into its reverse position and said second pilot valve connects the other of said valve chambers to the dwell control valve which controls the rate of shifting of the reverse valve into a reverse position.

3. In a grinding machine having a base, a reciprocable table, a piston and cylinder to reciprocate said table and a reversing mechanism therefor including a control valve having a slidably mounted valve stem, a reversing lever to actuate said stem, adjustable table dogs on said table to actuate said lever, a pilot valve fixedly mounted adjacent to each end of said valve stem, a reversing valve between said pilot valves which is slidably mounted on said valve stem, valve chambers between the pilot valves and the ends of the reversing valve, and a dwell control valve operatively connected with each of said pilot valves, said reversing lever being arranged positively to shift the reversing valve to cut off the exhaust of fluid from said cylinder, one of said pilot valves being arranged to admit fluid under pressure to one of said valve chambers to shift the reversing valve into a reverse position, and the other of said pilot valves being operatively connected to the dwell control valve so as to produce the desired dwell during table reversal.

4. In a grinding machine having a base, a reciprocable table thereon, a piston and cylinder to reciprocate said table, a table actuated reversing valve therefor, a transversely movable slide, a rotatable grinding wheel thereon, a nut and screw feed mechanism for said slide, means including a vane type fluid motor to actuate said feed mechanism, a fluid pressure actuated control valve for said motor, a pilot valve which is actuated in timed relation with said reversing valve to admit fluid to actuate said control valve during reversal of the table to cause an infeeding movement of the grinding wheel at the ends of the table stroke, a main control valve which is operatively connected to, start said table reciprocation and to render operative the vane type motor to produce an infeeding movement of the grinding wheel at each reversal of the table, and a manually operable feed wheel to rotate said screw and to actuate said main control valve to initiate a grinding cycle.

5. In a grinding machine having a base, a reciprocable table thereon, a piston and cylinder to reciprocate said table, a reversing valve therefor, a table actuated reversing lever to actuate said reversing valve, a transversely movable wheel slide, a rotatable grinding wheel thereon, means including a nut and screw feed mechanism for said slide, a gear mechanism to rotate said screw, means including a vane type fluid motor to actuate said gear mechanism, a fluid actuated control valve for said motor, a pilot valve to control the shifting movement of said control valve, operative connections between said reversing lever and said pilot valve whereby the pilot valve is actuated during reversal at the ends of the table stroke to cause an infeeding movement of the grinding wheel during reversal, a main control valve which is operatively connected to start said table reciprocation and to render operative the vane type motor to produce an infeed of the grinding wheel at reversal, and a manually operable feed wheel which is operatively connected to rotate said feed screw and to actuate said main control valve to initiate a grinding cycle.

6. In a grinding machine having a base, a longitudinally movable work table thereon, a piston and cylinder to reciprocate said table, a control valve therefor, a start and stop valve to control the exhaust of fluid from said cylinder, a rotatable grinding wheel, a transversely movable slide on said base, a rotatable grinding wheel on said slide, a piston and cylinder to move said slide rapidly to position said slide, a control valve therefor, means including a vane type fluid motor to feed said slide at a grinding speed, a control valve therefor, a pilot valve which is actuated by and in timed relation with the table control valve to actuate said latter control valve so as to produce an infeeding movement of the grinding wheel at each end of the table stroke, and a main control valve which is operatively connected to initiate a rapid approaching movement of the grinding wheel to start the table reciprocation and to render operative the vane type motor to produce an infeed of the grinding wheel at reversal.

7. In a grinding machine having a base, a reciprocable table thereon, a piston and cylinder to reciprocate said table, a control valve therefor, a start and stop valve to control the exhaust of fluid from said cylinder, a transversely movable grinding wheel slide on said base, a rotatable grinding wheel on said slide, a pis-

ton and cylinder to move said slide rapidly to position said grinding wheel relative to a work piece, means including a vane type fluid motor to move said slide so as to produce a grinding feed, a control valve therefor which is actuated by and in timed relation with the table reversing valve to produce an infeeding movement of the grinding wheel at the ends of the table stroke, and a main control valve which is operatively connected to initiate a rapid approaching movement of the grinding wheel to start the table reciprocation and to render operative the vane type motor to produce an infeeding movement of the grinding wheel at reversal.

8. In a grinding machine having a base, a longitudinally reciprocable table, a piston and cylinder to reciprocate said table, a control valve therefor, a start and stop valve to control the exhaust of fluid from said cylinder, a transversely movable grinding wheel slide on said base, a rotatable grinding wheel on said slide, a nut and screw feed mechanism for said slide, a piston and cylinder to move said screw in an axial direction rapidly to position the grinding wheel relative to a work piece to be ground, means including a vane type motor to rotate said screw, a control valve therefor which is actuated by and in timed relation with the reverse valve to produce an infeeding movement of the grinding wheel at the ends of the table stroke, a main control valve which is operatively connected to initiate a rapid approaching movement of the grinding wheel to start the table reciprocation and to render operative the vane type motor to produce an infeeding movement of the grinding wheel at reversal, and a manually operable feed wheel which is operatively connected to rotate said feed screw and to actuate said main control valve to initiate a grinding cycle.

9. In a grinding machine having a base, a longitudinally reciprocable table thereon, means including a manually operable hand wheel to traverse said table longitudinally, a rotatable work support including an electric motor driven work support on said table, means including a fluid pressure operated switch to control said motor, a piston and cylinder to reciprocate said table, a control valve therefor, a stop and start valve to control the exhaust of fluid from said cylinder, a transversely movable grinding wheel slide on said base, a rotatable grinding wheel on said slide, a nut and screw feed mechanism, a

- 5 piston and cylinder to move said feed screw axially rapidly to position the grinding wheel relative to a work piece to be ground, a control valve therefor, means including a vane type motor to rotate said feed screw, a control valve therefor which is actuated by and in timed relation with the reversing valve to produce an infeeding movement of the grinding wheel at the ends of the table stroke, and a main control valve which is operatively connected to actuate said first control valve so as to initiate a rapid approaching movement of the grinding wheel to start the work drive motor, to render the manual traverse wheel inoperative, to start the table reciprocation, and to render operative the vane type motor so as to produce an infeeding movement of the grinding wheel at reversal.
10. In a grinding machine having a base, a longitudinally reciprocable table thereon, means including a manually operable hand wheel to traverse said table longitudinally, a rotatable work support including an electric motor driven work support on said table, means including a fluid pressure operated switch to control said motor, a piston and cylinder to reciprocate said table, a control valve therefor, a stop and start valve to control the exhaust of fluid from said cylinder, a transversely movable grinding wheel slide on said base, means rotatably to support 15 a grinding wheel on said slide, a nut and screw feed mechanism, a piston and cylinder to move said feed screw axially rapidly to position the grinding wheel relative to a work piece to be ground, a control valve therefor, means including a vane type motor to rotate said feed screw, a control valve therefor which is actuated by and in timed relation with the reversing valve to produce an infeeding movement of the grinding wheel at the ends of the table stroke, and a main control valve which is operatively connected to actuate said first control valve so as to initiate a rapid approaching movement of the grinding wheel to start the work drive motor, to render the manual traverse wheel inoperative, to start the table reciprocation, and to render operative the vane type motor to produce an infeeding movement of the grinding wheel at reversal, and a manually operable feed wheel which is operatively connected to rotate said feed screw and to actuate said main control valve to initiate a grinding cycle.

HERBERT A. SILVEN.
